U.S. Appl. No. 29/294,502, filed Jan. 14, 2008, entitled "Absorbent Paper".

Primary Examiner—Robert M Spear

Assistant Examiner—Karen Acker

(74) Attorney, Agent, or Firm—Joel T. Charlton

CLAIM

The ornamental design for paper with pattern, as shown and described.

DESCRIPTION

This application relates to U.S. Design patent application Ser. No. 29/294,502, filed Jan. 14, 2008, entitled Absorbent Paper. The disclosure of the foregoing application is hereby incorporated into this application in its entirety by reference thereto.

The sole FIGURE is a left perspective view of paper with pattern. The reverse surface of the paper with pattern forms no part of the claimed design.
